UNITED STATES PATENT OFFICE.

EDWARD WILLIAMS, JR., OF WREXHAM, WALES.

MEANS FOR CONTROLLING THE OPENING OF RAILWAY-CARRIAGE DOORS.

1,211,990.

Specification of Letters Patent.

Patented Jan. 9, 1917.

Application filed June 7, 1916. Serial No. 102,368.

To all whom it may concern:

Be it known that I, EDWARD WILLIAMS, Jr., a subject of the King of England, residing at Wrexham, in the county of Denbighshire, North Wales, United Kingdom of Great Britain, have invented new and useful Improved Means for Controlling the Opening of Railway-Carriage Doors, of which the following is a specification.

10 This invention has reference to means for controlling the opening of railway carriage doors, in which there is used in connection with each carriage or coach, an actuating means adapted to be actuated by steam (or other fluid pressure) supplied from the engine, the opening of the doors being therefore controlled from the engine, or the guard or conductor of the train, or other person in authority; so that between the stations, 15 20 the doors on each side of the train may be locked by this mechanism, and cannot be opened by the passengers, but when the train gets to a station all the doors can be simultaneously unlocked and freed.

25 The invention is illustrated in the annexed drawings in which—

Figure 1 is a side elevation of a railway carriage showing the mechanism applied; Fig. 2 is a side elevation showing a fluid pressure actuator; Fig. 3 is an end view of same; and Figs. 4 and 5 show respectively right and left hand levers connected with the gear. Fig. 6 is a side elevation of the actuator showing the internal parts in dotted lines; and Figs. 7 and 8 side elevation and end view of the internal part or piston.

Referring now to the drawings, 1 represents the steam or other fluid pressure pipe, which each coach is fitted with; 2 generally 40 45 designates the actuating device; 3 are the connecting rods leading from the actuator to the various locks of the carriage; 4 represents the spindles of these locks, which in themselves may be of any known suitable kind; and 5 are pivoted bell crank levers by which motion of the rods 3 is conveyed to the chains 6, connecting the levers 5 with the locks 4.

The pipe 1 is provided at each end with 50 any suitable form of coupling, for connecting it up with the adjacent carriages in the known way.

The actuators 2 consist of a cylinder 8, within which is a piston 9, fixed on a shaft

10, extending through the cylinder covers 55 8, and supported by bearings in them. The piston 9 consists of two disks, one at each side, with a plate 12 between them at the lower part, and a segmental shaped plate 13 extending from the plate 12 upward in 60 each direction to the edge of the piston, so that between the plate 12, and the plates 13 on each side of it, there is formed two chambers in the lower part of the piston; and these chambers lie in the lower part of the 65 cylinder, to which lower part steam or fluid pressure is conducted by the pipe 3, through the branches 14, so that it can enter the chambers of the piston referred to, and act on the plate 12. The plate 12 also extends 70 up from the plate 13 to the upper part of the piston, as shown in Figs. 6, 7 and 8.

The steam operates upon the piston plate or blade 12 by impact; and the apparatus will be so arranged that the steam is only 75 required to unlock the door by the locks 4 when the train has come to a stand-still at a station; the locks being of any known self-locking type, which will allow the doors being closed when pressed in and locked; 80 but only prevented from being opened.

The motor or actuator cylinder 8 is in two halves connected together by a flange 15; and the cylinder is carried from the bottom of the carriage or vehicle by a 85 bracket 16. The shaft 10 is connected with the connecting rods 3, on each side of the actuator 2, by means of a double arm lever 18 on the shaft, and connecting chains 19; and one of the locks 4 is directly worked 90 from the shaft 10 by a double arm lever 20, also on the shaft 10, and chains 21, which at their ends are joined up with the lock actuating chain 6. By this actuator, and the various rods, levers, chains, the locks of 95 a carriage or coach can be worked from the one actuator.

The chains 6 may pass up to the locks 4 through a hole in the bottom of the carriage; and these locks may consist of a short arm 100 or tongue fixed on a lock spindle, on which also an arm or lever is fixed, and to the end of which the chain 6 will be attached. When the said lever is pulled down by the chain, the locking tongue, which normally would 105 engage the door at any suitable point, and in any known way, would be withdrawn, and so the doors will be unlocked. The lock

spindle may pass through the frame of the door so that it can be operated by a key on the outside.

What is claimed is:—

- 5 1. In means for controlling the opening of railway carriage doors, the combination of an actuator adapted to be operated by steam or fluid pressure, comprising a cylinder and vibratory piston or fan device therein, operated by impact of the steam supplied to the cylinder; and connecting means between said fan or piston and locks on the carriage for controlling the opening of the doors; substantially as set forth.
- 10 2. In means for controlling the opening of railway carriage doors the combination of a motor or actuator adapted to be operated by steam or fluid pressure comprising a cylinder and vibratory piston or fan device therein operated by impact of the steam supplied to the cylinder and connecting means between said fan or piston and locks on the carriage for controlling the opening of the doors, and connecting rods and levers 20 between said actuator or motor and various locks controlled thereby on the carriage.
- 15 3. In means for controlling the opening of railway carriage doors the combination of a motor or actuator adapted to be operated by steam or fluid pressure comprising a cylinder and vibratory piston or fan device therein operated by impact of the steam supplied to the cylinder and connecting

means between said fan or piston and locks on the carriage for controlling the opening of the doors, and wherein the connections between the shaft of the piston of the actuator or motor and the locks is effected by double lever chains on each side of said shaft, one end of the chains being connected to each arm. 35 40

4. In combination, a railway car having a plurality of doors, a lock for each door, an actuator including a casing inclosing a vibratory element operated by fluid pressure, pipes communicating with the casing to supply fluid pressure thereto to operate the vibratory element, and connecting means between the vibratory element and the locks for controlling the opening of the doors. 45

5. In combination, a railway car having a plurality of doors, each door having a lock, an actuator including a vibratory element and shaft therefor, pipes for supplying fluid pressure to the actuator, arms extending from the shaft, and connections between the arms and the locks, whereby when fluid pressure acts on either side of the vibratory element all the locks will be released. 50 55

In testimony whereof I have signed my name to this specification in the presence of two subscribing witnesses.

EDWARD WILLIAMS, JUNIOR.
